UNITED STATES PATENT OFFICE.

ROBERT H. BRAUCH, OF HALEDON, NEW JERSEY.

CREEL.

1,246,229.

Specification of Letters Patent.

Patented Nov. 13, 1917.

Application filed May 10, 1917. Serial No. 167,648.

To all whom it may concern:

Be it known that I, ROBERT H. BRAUCH, a citizen of the United States, residing at Haledon, in the county of Passaic and State 5 of New Jersey, have invented certain new and useful Improvements in Creels, of which the following is a specification.

The object of this invention is to provide a creel for use in warping which shall have 10 provision at both sides thereof for receiving warp supply spools and so constructed that while the warp is being delivered from the spools at one side thereof the other side may be equipped with freshly filled spools 15 and the warp threads thereof "reeded" and otherwise made substantially ready, upon reversing the creel side for side, to continue the warping without undue delay when the first set of spools becomes exhausted. To this end my invention consists 20 in a creel having means to hold warp spools arranged in two sets, one at each side thereof, and a pair of warp guiding means arranged to be movable on the creel frame 25 each into and out of the plane of progress of the warp from the creel, so that while one is in said plane and functioning with reference to the set of spools to which it appertains the other may be disposed out 30 of said plane and hence out of the way of the threads being delivered to the warping machine from the said set of spools. The guiding means preferably corresponds, as herein shown and described, to the usual construction in that each consists of a reed and 35 a cross-bar and is arranged at the top of the frame, the movement thereof with reference to the plane of progress of the warp being consequently up and down.

40 In the accompanying drawing,

Figure 1 is a side elevation of a creel embodying my invention and showing the warp being taken from the set of spools at one side of the same under the control of the 45 corresponding guiding means, the other side being in condition to receive a fresh set of spools and have the threads thereof "reeded" while the warp is progressing with reference to the threads of the first set of spools;

50 Fig. 2 is a fragmentary elevation of one side of the creel; and

Fig. 3 is an enlarged end elevation of the upper part of the creel showing one guiding means elevated and the other depressed.

55 a is the usual frame, the same having according to this invention two sets of skewers

b, one at each side thereof, to receive spools or bobbins c. The skewers at one side of the creel in Fig. 1 are shown filled with bobbins, the threads progressing therefrom 60 in the usual plane of progress d of the warp toward the warping machine (not shown). In the present instance there are shown at the top of the frame two cross-beams e, one at each side of the frame. The warp guiding means for the two sets of spools are arranged on these two cross-beams, one on each, and as they are substantially alike a description for one will serve for both.

Hinged to the top of the frame, as by 70 hinges f, so as to swing outwardly and downwardly from the working or warp guiding position, is a pair of brackets g which are rigidly connected by an elongated plate or board h secured thereto by screws i. Inset 75 in the outer edge of this board is a horizontal cross-bar j, suitably secured thereto. The reed k is secured to the inner face of the board h, preferably so as to converge 80 downwardly with reference thereto; a practical construction relating to the attachment of the reed to the board is shown in the drawing and consists in forming a longitudinal cross-sectionally angular groove l in the inner face of the board, setting the lower 85 edge of the reed therein, and then securing the reed in place by screws m. This construction gives the desired spacing between the cross-bar j and the reed in the warp plane.

90 The form of the brackets is such that when the structure comprising the same, board h, cross-bar j and reed k is in working position the said structure somewhat overhangs the corresponding side of the creel frame, resting at that time on the top of the beam e, and when said structure is swung down, resting then against a suitable stop n, the reed projects laterally well outwardly of the cross-bar j (left of Fig. 1).

100 To hold each guiding means in the elevated position I attach at one or each end thereof a hook o adapted to engage an eye p on the frame.

105 In the use of the improved creel, the skewers at one side of the same being filled with spools and the guiding means appertaining thereto being elevated as shown at the right in Fig. 1, the warp proceeds from said spools up over the corresponding cross-bar j and through the corresponding reed k; 110 at this time the guiding means for the other

side of the creel is depressed out of the plane of progress *d* of the warp, so as not to interfere therewith. While the warping is proceeding with respect to the threads from the 5 set of spools mentioned, the empty spools can be removed from the skewers at the other side of the creel frame and replaced with filled ones, whereupon the threads from these spools are passed through the reed of 10 the corresponding guiding means, *i. e.*, outwardly of the corresponding cross-bar *j*. The threading of the reed will be facilitated by resorting to a well-known expedient consisting in tying their ends to the cut-off end 15 portions *q* of previously warped threads left threaded through the reed. When the warp has been completed with respect to the set of spools at the right in Fig. 1, the creel is reversed, side for side, and a fresh set of 20 spools, with the threads thereof all reeded, now being in operative position for warping, the guiding means appertaining to said set

of spools is elevated and the other guiding means lowered and said threads extended to the reel of the warping machine. 25

Having thus fully described my invention, what I claim as new and desire to secure by Letters Patent is:—

1. A reversible warping creel including an upright frame, means at opposite sides thereof to receive warp spools, and separate warp-guiding means arranged on the creel frame and each being movable in an up and down direction into and out of the plane of progress of the warp from the creel. 30

2. A reversible warping creel including an upright frame, means at opposite sides thereof to receive warp spools, and separate warp-guiding means arranged on the creel frame and each being movable pivotally on an axis 40 parallel with and into and out of the plane of progress of the warp from the creel.

In testimony whereof I affix my signature.

ROBERT H. BRAUCH
